US0D1101427S

(12) **United States Design Patent** (10) **Patent No.:** **US D1,101,427 S**
Kien et al. (45) **Date of Patent:** **** Nov. 11, 2025**

(54) **PAPER PRODUCT**(71) Applicant: **The Procter & Gamble Company**,
Cincinnati, OH (US)(72) Inventors: **Kathryn Christian Kien**, Cincinnati,
OH (US); **Deborah Sue Slovut**,
Madeira, OH (US); **Jeffrey Moss**
Vaughn, Colerain Township, OH (US)(73) Assignee: **The Procter & Gamble Company**,
Cincinnati, OH (US)(**) Term: **15 Years**(21) Appl. No.: **29/919,529**(22) Filed: **Dec. 5, 2023****Related U.S. Application Data**

(60) Division of application No. 29/616,972, filed on Sep. 11, 2017, now Pat. No. Des. 1,045,407, which is a continuation of application No. 14/301,392, filed on Jun. 11, 2014, now Pat. No. 10,814,513, and a continuation of application No. 14/301,415, filed on Jun. 11, 2014, now Pat. No. 10,005,197, and a continuation of application No. 14/301,384, filed on Jun. 11, 2014, now Pat. No. 11,254,024.
